for John S. Crane, Atty.

UNITED STATES PATENT OFFICE.

PAUL B. LIEBERMANN, OF EAST ORANGE, NEW JERSEY, ASSIGNOR, BY MESNE ASSIGNMENTS, TO HYATT ROLLER BEARING DIVISION, UNITED MOTORS CORPORATION, OF HARRISON, NEW JERSEY, A CORPORATION OF NEW YORK.

HANGER-BOX.

1,249,431.

Specification of Letters Patent. Patented Dec. 11, 1917.

Application filed May 9, 1917. Serial No. 187,556.

To all whom it may concern:

Be it known that I, PAUL B. LIEBERMANN, residing at No. 52 Warrington place, in East Orange, county of Essex, State of New Jersey, have invented certain new and useful Improvements in Hanger-Boxes, fully described and represented in the following specification and the accompanying drawings, forming a part of the same.

10. This invention relates to a hanger-box provided with a novel means of supplying oil thereto in such quantity only as will serve for lubrication without running out of the ends of the box.

15. Such hanger-boxes are provided with seats upon opposite sides at the middle of their length by which they may be fitted between the legs of a hanger and guided in any practical adjustment that may be necessary.

20. In the present construction, an oil-chamber for retaining a store of oil is provided in the middle of the hanger-box intermediate to the said seats, and the hanger-box has nozzles at its opposite ends containing each a cylindrical bearing-roll seat with a collar at its outer end to embrace the shaft.

25. To avoid any escape of oil from the lowest point in this collar, the oil must be supplied to the box from a source no higher than the bottom of the collar, and to supply both of the roll-chambers equally, the supply should be delivered to the oil-chamber in the middle of the box.

30. This is effected by locating a pocket at the side of one of the nozzles with its top not higher than the bottom of the collar, and extending a passage from this pocket obliquely into the oil-chamber between the hanger-legs.

35. Such an oblique arrangement is required by the disposition of the pocket upon one of the nozzles as the legs of the hanger prevent its being applied to the middle portion of the box.

40. The location of the pocket close to one of the hanger-legs permits the passage to be extended from the pocket into the central oil-chamber, by drilling a hole from the pocket obliquely into the said chamber, the outer end of the hole upon the outer side of the pocket being permanently closed by a plug after the passage is formed.

45. By this construction, the hanger-box can

be made with a contracted waist at the middle of its length, thus enabling it to fit within a relatively small space between two hanger-legs.

50. The construction will be understood by reference to the annexed drawing, in which Figure 1 is a longitudinal section of the hanger-box with the anti-friction bearing-rolls omitted; Fig. 2 is a plan of the lower part of the box with a section of the hanger-legs; Fig. 3 is a section of the hanger-box taken on line 3-3 in Fig. 2; and Fig. 4 is a section through one of the bearing-roll chambers taken on line 4-4 in Fig. 2 and looking toward the middle portion of the box.

55. *a* designates the upper half or cap of the box which is connected with the lower half *b* by lugs and bolts *c*. The cylindrical bearing-roll chambers *d* are formed within cylindrical nozzles *f* at opposite ends of the contracted waist, which has the seats *g* for the hanger-legs *j* at its opposite sides and has the oil-chamber *h* between such seats.

60. The outer ends of the nozzles *f* are provided with collars *i* adapted to snugly fit the shaft.

65. A partition *k* divides the lower part of each bearing-roll chamber from the oil-chamber *h*, and has perforations *l* to conduct oil from the oil-chamber into the lower part of the chamber *d*. The oil is supplied to the chamber *h* by a passage *m* extended obliquely from an oil-pocket *n*, which is formed upon the side of one of the nozzles next the edge of the hanger-seat.

70. The top of this pocket, as shown in Fig. 3, is about on a level with the bottom of the collar *i* and it is therefore impossible to supply oil to the oil-chamber *h* above the level of that collar and no overflow from the collar could therefore occur.

75. The passage *h* is necessarily oblique because the pocket cannot be located upon either side of the oil-chamber, as it would interfere with the hanger-legs, but its location close to the edge of the hanger-leg or seat *g* permits the supply of the oil-chamber from the outer side of the nozzle and limits the depths of the oil in the chamber to the desired level.

80. A lid *o* is shown upon the pocket in Fig. 3, but such lid is not essential to the operation of the invention, as the formation of

the pocket at the right level enables it to perform all its functions. The pocket, when the lid is raised, is open to inspection, and the height of the oil in it corresponds to its 5 height in the oil-chamber, so that the pocket serves as a gage to the depth of the oil as well as a preventive of overflow.

Two holes *l* are shown in each of the partitions *k* to deliver the oil from the oil-chamber *h* to the bearing-roll chambers *d*; and the use of two holes is desirable because the sediment from the oil accumulates in the bottom of the oil-chamber and might clog a single hole if such were used. The 10 provision of two holes thus forms an additional security against any such obstruction.

A single hole embodies the invention, as well as an open notch in the partition, and 20 I have therefore claimed a perforated partition as an element of the invention.

Having thus set forth the nature of the invention what is claimed herein is:

1. A hanger-box having nozzles at its 25 opposite ends containing cylindrical bearing-roll chambers with collars at their outer ends to embrace the shaft, an oil-chamber intermediate to the bearing-roll chambers separated from each by a perforated parti- 30 tion beneath the shaft, and a supply-pocket projected from one side of the hanger-box and having a channel communicating with

the said oil-chamber, the top of such pocket being a trifle lower than the bottoms of the collars to prevent any oversupply of oil 35 to the chambers.

2. A hanger-box having nozzles at its opposite ends containing cylindrical bearing-roll chambers with collars at their outer ends to embrace the shaft, vertical seats 40 upon opposite sides of the box between the said nozzles to receive the legs of a hanger, an oil-chamber within the space between the said seats separated from the bearing-roll chambers by a perforated partition, and a 45 supply-pocket projected from one side of the hanger-box at the edge of one of the seats and having a channel extended obliquely into the oil-chamber between the 50 seats.

3. A hanger-box divided longitudinally into a base and cap and having nozzles at its opposite ends containing cylindrical bearing-roll chambers with collars at their outer ends to embrace the shaft, an oil-chamber 55 intermediate to the bearing-roll chambers separated from each by a perforated partition beneath the shaft, and a supply-pocket projected from one side of the hanger-box and having a channel communicating with 60 the said oil-chamber.

In testimony whereof I have hereunto set my hand.

PAUL B. LIEBERMANN.
